UNITED STATES PATENT OFFICE.

MILTON McCARTER AND RICHARD VENIS, OF COLFAX, INDIANA.

WIRE-WRAPPING DEVICE.

1,160,182.

Specification of Letters Patent. Patented Nov. 16, 1915.

Application filed May 27, 1915. Serial No. 30,801.

To all whom it may concern:

Be it known that we, MILTON McCARTER and RICHARD VENIS, citizens of the United States, residing at Colfax, in the county of Boone, State of Indiana, have invented a new and useful Wire-Wrapping Device, of which the following is a specification.

The present invention appertains to wire wrapping devices, and is particularly an improvement over the wire working device disclosed in the patent to Milton McCarter, No. 1,144,217, granted June 22, 1915.

It is the object of the invention to provide a wire wrapping device embodying two coöperable rotary members assembled with one another and with the frame in a unique manner, whereby when one member is rotated in one direction, the slots of the two members will be brought into registration for receiving the wire, and when the said member is rotated in the other direction, the slots will be brought out of registration, to lock the wire in place when the wrapping or twisting action is started.

It is also within the scope of the invention to improve the implement generally in its construction and details, to enhance the utility thereof, and to render the same comparatively simple, compact and inexpensive in construction, as well as rendering the device thoroughly practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a side elevation of the improved device. Fig. 2 is a longitudinal section thereof taken on the line 2—2 of Fig. 3. Fig. 3 is another elevation of the device looking at right angles to the line of view in Fig. 1, portions being broken away. Fig. 4 is a sectional detail taken on the line 4—4 of Fig. 1. Fig. 5 is a fragmental detail of one arm of the frame. Figs. 6 and 7 are views illustrating the adjacent or inner sides of the rotary disks.

In carrying out the invention, there is

provided an approximately U-shaped frame or body 1, one arm of which is in the form of a relatively thick ear 2 having a circular opening or bore 3 and an entrance slot 2^a extending from the opening 3 to the free end of the arm or ear 2. The free end of the other arm of the frame 1 is provided with an open slot 4 for receiving the wire. The intermediate or yoke portion of the frame 1 is provided with an outstanding hub or sleeve 5 through which a spindle or shaft 6^a is journaled, the outer or projecting end of the shaft or spindle 6^a having a square tapered portion 6 for the engagement of a crank brace or other suitable contrivance for rotating the shaft 6^a. A bevel gear 7 is secured to that end of the shaft 6^a within the frame 1 and coöperates with the rotary twisting or winding head 8 journaled with 75 in the opening 3 of the arm 2. This twisting head 8 embodies an inner disk 9 journaled within the opening 3, and having a bevel gear 10 intermeshing with the bevel gear 7, and the head 8 includes a second 80 disk 11 journaled within the opening 3 and bearing lightly against the disk 9. Arcuate plates 12 and 13 are secured to the inner and outer sides of the arm or ear 2 and have their edges slightly overlapping the 85 remote faces of the disks 9 and 10, respectively, to retain the disks for rotation within the opening 3. The disk 9 and its gear 10 are provided with a radial slot 14, and the disk 11 is also provided with a radial 90 slot 15. The side of the disk 9 adjacent the disk 11 is provided with an arcuate slot or groove 16 receiving a lug 17 projecting from that side of the disk 11 adjacent the disk 9, whereby when the lug 17 strikes one end 95 of the slot 16, the radial slots 14 and 15 of the inner and outer disks 9 and 11, respectively, will be brought into registration. The outer side of the disk 11 is provided at one side of the slot 15 with an outstanding lug 18 having a notch 19 for receiving the end portion of a wire, whereby said end portion of the wire will be carried around with the disk 11.

In operation, to apply the device to a wire 105 20, the arm or ear 2 is placed in proper position whereby the wire 20 is received by the entrance slot 2^a, so as to bear against the peripheries of the disks 9 and 11. The shaft or spindle 6^a is then rotated properly in any 110 suitable manner, for rotating the disk 9 clockwise, as seen in Fig. 3, and this will

cause the disk 9 to rotate with respect to the disk 11 until the lug 17 strikes the respective end of the slot 16, to bring the slots 14 and 15 into registration. Then, when the 5 rotation of the disk 9 is continued, both of the slots 14 and 15 of the two disks will be brought into registration with the entrance slot 2^a, and the wire will be received by the slots 14 and 15, and the wire will also be received by the slot 4. It is of course evident that before applying the device to the wire, the slots 14 and 15 may be brought into registration with one another and into registration with the slot 2^a so that the device may 10 be readily applied to the wire, but the above described method of applying the device to the wire is an exceedingly simple and convenient one. The twisting operation is then carried out by engaging the notched lug 18 15 with the end portion 21 of another wire which is to be twisted or wrapped upon the wire 20, and in which event the shaft 6^a is rotated in the opposite direction, to rotate the disk 9 correspondingly. The disk 11 20 will be momentarily held stationary by its frictional engagement with the arm 2 and plate 13, while the disk 9 rotates through an arc defined by the slot 16, in which event the lug 17 will strike the respective end of 25 the slot 16, to carry the disk 11 with the disk 9. In this manner, the slots 14 and 15 of the two disks are brought out of registration, to automatically lock the wire 20 within the twisting head 8, whereby the device 30 will be properly held upon the wire 20 during the twisting operation. When the head 8 is rotated, the end portion 21 of the second wire will be twisted or wrapped around the wire 20 to complete the splice being made, or 35 the work being done. The device may be readily removed by again rotating the shaft 6^a so that the slots 14 and 15 both register with the slot 2^a, so that the device may be 40 readily drawn off of the wire 20.

45 The present implement may be employed in different capacities for working wire or equivalent elements, and is particularly designed for wrapping or winding one wire or portion about another for splicing or the like. Particular attention is directed to the manner in which the disks 9 and 11 are assembled with one another, whereby they have limited oscillatory movements relative 50 to one another, and attention is also directed to the manner in which the disks 9 and 11 are assembled with the frame. One of the disks is adapted to be rotated, while the other disk has wire engaging means, which

in connection with the limited movement allowed between the disks, provides for the 60 automatic locking of the device upon the wire as aforesaid.

Having thus described the invention, what is claimed as new is:

1. In a wire working implement, a pair 65 of disks having radial slots adapted to be brought into and out of registration and having interengageable means whereby the disks have limited oscillatory movement relative to one another, one disk being 70 adapted to be rotated, and the other disk having wire engaging means.

2. In a wire working implement, a frame, a pair of disks journaled within the frame and having radial slots adapted to be 75 brought into and out of registration and interengageable means whereby the disks have limited oscillatory movement relative to one another, the frame having an entrance slot with which said slots are adapted to register, one disk having wire engaging means, and means carried by the frame and coöperable with the other disk for rotating the same.

3. In a wire working implement, a pair of 85 disks arranged adjacent one another, the disks having radial slots adapted to be brought into and out of registration and having interengageable means whereby the disks have limited oscillatory movement 90 relative to one another, one disk having an arcuate slot, and the other disk having a lug received by said arcuate slot, one disk being adapted to be rotated and the other disk having wire engaging means. 95

4. In a wire working implement, a frame having an opening and an entrance slot extending from said opening, a pair of disks journaled within said opening adjacent one another, arcuate plates secured to the frame 100 and partially overlapping the remote sides of said disks, the disks having radial slots adapted to be brought into and out of registration, one disk having an arcuate slot and the other disk having a lug received by said 105 arcuate slot, one disk having wire-engaging means, and means carried by the frame for rotating the other disk.

In testimony that we claim the foregoing as our own, we have hereto affixed our signatures in the presence of two witnesses.

MILTON McCARTER.
RICHARD VENIS.
